CASING FOR A DATA RECORDING MACHINE

Donald R. Biegel, North Hollywood, Calif., assignor to
Datanamics, Inc., Canoga Park, Calif., a corporation
of California

Filed Feb. 28, 1961, Ser. No. 64,090

Term of patent 14 years

(Cl. D64—11)

FIG. 1.

FIG. 2.

FIG. 1 is a front perspective view of a casing for a data recording machine showing my new design; and
FIG. 2 is a back perspective view thereof.

I claim:

The ornamental design for a casing for a data recording machine, as shown.
